UNITED STATES PATENT OFFICE.

GEORGE I. ARNOLD, OF LONACONING, MARYLAND.

HENHOUSE DOOR.

Application filed August 2, 1926. Serial No. 126,695.

This invention relates to an improvement in hen house doors.

The object of the invention is to allow the chickens to automatically release the hen house door in the morning, while at the same time to insure that the door is closed from the outside during the night, for preventing the entrance of animals such as prey upon the fowls.

10 This invention obviates the undesirable necessity usually felt of requiring that a person open the hen house door in the morning for the release of chickens from such hen house, and permits of self release by the chickens.

15 With these objects in view, the invention is constructed of a door frame having a window or light opening in the top thereof, and below which is a gravity actuated door, pivoted at the bottom to drop down to release the chickens. In order to hold the door in its closed position, it is provided with a catch engaged by a hook carried by a pivoted platform which is mounted below the window or light opening so that when the chickens fly towards such window they will move the platform to release the door and it will drop to its open position by gravity.

20 Suitable means is provided for limiting the movement of the platform in order that it will not drop down sufficiently far to close the door-way.

In the accompanying drawings:

25 Fig. 1 is a vertical sectional view through the device;

Fig. 2 is a rear elevation of the same;

Fig. 3 is a perspective view of the door, detached; and

Fig. 4 is a perspective view of the platform and associated mechanism.

30 The numeral 1 indicates the frame work of a hen house or similar chicken confining enclosure having a metal frame work 2 secured thereto, which is provided with a flange 3 around the edges thereof, as clearly shown in Fig. 1. This frame 2 has the upper end thereof closed by a glass covered window 4 interposed between the upper flange 3 and a cross bar 5.

35 Hinged as at 6 to the lower flange 3 at the rear edge thereof is a door 7 which extends upwardly to fill a door-way 8 formed in the metal frame 2, the upper end of the door 7 engaging the cross strip 5 and having its rearward movement limited thereby. The door 7

slants, as shown in Fig. 1, so that it will drop down into the dotted line position, as shown in this figure, by gravity, when released. Secured to the back face of the door 7 near the upper edge thereof is a catch 9, as shown in Figs. 1 and 3, in position to be engaged by a hook 10 formed by turning down the end of a platform or treddle 11 pivotally mounted on the bar 12 which has the opposite ends thereof received in bearing plates 13 extending outwardly from the side flanges 3. Lugs 14 are bent inwardly from one of the plates 13 in position to engage an arm 15 fixed on the pivot bar 12 for limiting the upward and downward movement of the platform or treddle 11. A weight 16 is mounted on the front end of the platform or treddle 11 in order to counterbalance said platform and to normally hold it in its downward position to engage the catch 9.

40 In order to close the door 7 from the outside, whenever it is desired to keep such door closed so that it may not be opened from the inside, a suitable latch 17 is pivotally connected with the strip 5 in position to be turned down over the upper edge of the door.

45 In use, when the chickens are in the hen house for the night, the door is closed by being raised from the dotted line position of Fig. 1 to the full line position of said figure, and the catch 9 is engaged by the hook 10 of the platform so that the door is in its set and closed position, preventing its being opened by animals or unauthorized persons from the outside.

50 In the morning when the chickens desire to be released they will fly or jump toward the glass window 4 and either rest upon or engage the platform or treddle 11, moving the rear end of the same downward and disengaging the hook 10 from the catch 9, thus allowing the door 7 to be opened by gravity. This leaves the door-way 8 entirely unobstructed and the chickens may then pass from the hen house at will. The weight 16 will normally hold the front end of the platform 11 down in the dotted line position indicated in Fig. 1, but this downward movement is limited by the lower lug 14, the upper lug 14 also limiting the upward movement of this platform.

55 It may thus be seen that a door has been provided for a hen house or chicken enclosure which may be automatically opened by the chickens without necessitating the release of

them by a person and, yet, preventing the unauthorized opening of the door by animals or unauthorized persons.

I claim:

1. A device of the character described including a frame having inturned flanges therearound, a window in the upper portion of the frame, a cross bar at the lower edge of the window, an inclined gravity controlled door hinged at its lower edge to the outer edge of one of the flanges, and normally extending into engagement with the cross bar, a catch carried by said door, a hook in position to engage the catch to normally hold the door closed, a platform for actuating said hook, a bar for pivotally supporting the platform, and bearing plates extending outwardly from the flanges for supporting the opposite ends of said bar, said platform being arranged adjacent the upper end of the door and the lower end of the window.

2. A device of the character described including a frame having inturned flanges therearound, a window in the upper portion of the frame, a cross bar at the lower edge of the window, an inclined gravity controlled door hinged at its lower edge to the outer edge of one of the flanges, and normally extending into engagement with the cross bar, a catch carried by said door, a hook in position to engage the catch to normally hold the door closed, a platform for actuating said hook, a bar for pivotally supporting the platform, bearing plates extending outwardly from the flanges for supporting the opposite ends of said bar, said platform being arranged adjacent the upper end of the door and the lower

end of the window, an arm fixed to said bar, lugs extending inwardly from one of the bearing plates in position to be engaged by said arm for limiting the pivotal movement of said platform, and a counterbalance carried by the front end of the platform adjacent the hook.

3. A device of the character described, including a frame, a door hinged therein, a catch carried by said door, bearing plates extending outwardly from the frame, a bar supported in said bearing plates, a pivotally mounted treddle supported on said bar and terminating in a hook for engaging the catch on the door, and means for limiting the pivotal movement of the treddle.

4. A device of the character described including a frame having inturned flanges therearound, a window in the upper portion of the frame, a cross-bar at the lower edge of the window, an inclined door hinged at its lower edge to the inner edge of one of the flanges and normally extending into engagement with the cross-bar, and means for holding said door in its normal position.

5. A device of the character described including a frame having bearing plates connected therewith, a door mounted on the frame, a treddle for releasing the door, a bar mounted between the bearing plates and pivotally supporting the treddle, an arm carried by said bar, and means carried by at least one of the bearing plates for co-operating with said arm to limit the pivotal movement of the treddle.

In testimony whereof I affix my signature.

GEORGE I. ARNOLD.
